UNITED STATES PATENT OFFICE.

JOSEPH KLOHE, OF NEW YORK, N. Y.

MITER TOOL.

Application filed February 16, 1922. Serial No. 537,127.

To all whom it may concern:

Be it known that I, JOSEPH KLOHE, a citizen of the United States, and a resident of the city of New York, borough of Bronx, 5 in the county of Bronx and State of New York, have invented a new and Improved Miter Tool, of which the following is a full, clear, and exact description.

This invention relates to mitring tools, 10 and has for an object to provide an improved construction particularly adapted for mitring rules used in printing.

Another object in view is to provide a mitring tool, wherein a strip of substantially 15 any material may be mitred at a correct angle with a minimum effort.

A still further object of the invention is to provide a construction wherein two or more rules or other articles may be simultaneously mitred for producing a square 20 corner when fitted together.

In the accompanying drawings:

Figure 1 is a top plan view of a complete mitring machine, disclosing one embodiment 25 of the invention;

Figure 2 is a sectional view through Fig- 1, approximately on line 2—2;

Figure 3 is an enlarged detail perspective 30 view showing the cutter disclosed in Figure 1; and

Figure 4 is a fragmentary elevation of several mitred rules fitted together for producing a border.

Referring to the accompanying drawing 35 by numeral, 1 indicates the frame of the mitring tool which is designed particularly for mitring rules and other articles used for printing, though it may be used for mitring any desired article. The frame 1 is an old 40 and well known structure and is provided with runways for receiving a reciprocating head 2, which as far as the runways is concerned, is old and well known. This head is provided with overhanging portions 3 for receiving the arm 4, which arm is pivotally mounted at 5 on frame 1, whereby the head may be moved upwardly and downwardly 45 with ease. The overhanging members 3 and the hand lever 4 is old and well known. The head 2, however, is provided with a slot 6 through which a clamping bolt 7 passes, said clamping bolt being threaded into the cutter 8 whereby the cutter may be clamped against the upper section 9 of the head 2. 50 Any desired number of set screws 10 may be used for assisting the clamping bolt 7 in

holding the cutter 8 rigidly in a given position in respect to the head 2. The cutter 8 is provided with a cutting end 11, which end is formed with a notch 12 and a straight section 13, the straight section 13 being adapted to trim off the end of a rule, or to cut a slug or other article as desired. The walls of the cutter 8 at the notch 12 incline somewhat, as shown in Figure 2, so as to 60 provide sharp cutting edges 14. The side cutting edge 14 is arranged at an angle, usually a 45° angle, from the sides 15 of the cutter 8. A guide plate 16 coacts with the cutter 8 so that a rule 17, or other article can 65 be held in place against the guide 16 while being trimmed. The guide plate 16 is provided with a lug 18 fitting into a suitable aperture 19 in the supporting plate 20. The guide plate 16 is also provided with a 70 threaded extension 21 projecting through the slot 22 in the plate 20, whereby the nut 23 may readily clamp the plate 16 in any ad- 75 justed position. As shown in Figure 1, two rules are arranged against the guide plate 16, 80 said rules being capable of being slid man- ually against the cutter 8 or in line therewith. When the parts are arranged, as shown in Figure 1, and the rules 17 are forced toward the cutter and the cutter is moved upwardly 85 and downwardly, said rules will be mitred simultaneously whereby they may readily fit together, as shown in Figure 4. If some other angle of miter is desired than a 45° angle the plate 16 may be adjusted to secure 90 the desired angle and then the cutter 8 op- erated.

I claim:

1. In a cutting machine of the class de- 95 scribed, a reciprocating head and V-shaped cutter therein, and a gauge extending in the direction of the open end of said V-shaped cutter.

2. In a cutting machine of the class de- 100 scribed, a reciprocating head and V-shaped cutter therein, and a gauge extending in the direction of the open end of said V-shaped cutter, said gauge adjustably mounted upon a pivoted support adjacent said cutter.

3. In a cutting machine of the class de- 105 scribed, a reciprocating head and V-shaped cutter therein, and a gauge extending in the direction of the open end of said V-shaped cutter, said gauge adjustably mounted upon a pivoted support adjacent said cutter and 110 having its inner end projecting within the V-shaped opening of said cutter.

4. In a cutting machine of the class described, a reciprocating head and V-shaped cutter therein having side cutting edges, and a gauge extending in the direction of the open end of said V-shaped cutter, said V-shaped cutter having a substantially transverse intervening portion connecting the side cutting edges thereof.
5. In a cutting machine of the class described, a reciprocating head and V-shaped cutter therein having side cutting edges, and a gauge extending in the direction of the open end of said V-shaped cutter, said V-shaped cutter having a substantially transverse intervening portion connecting the side
- cutting edges thereof, and a transverse cutting edge laterally of said V-shaped cutting edges.
6. In a machine of the class described, a vertically reciprocating substantially V-shaped cutting head having a laterally extending cutter, and a gauge movably mounted adjacent said head and extending therefrom.
7. In a machine of the class described, a vertically reciprocating head and V-shaped cutter therein, and means in combination therewith for guiding slugs into the open side of said V-shaped cutter.

JOSEPH KLOHE.
